UNITED STATES PATENT OFFICE

GEORGE A. BONGE, OF HEARNE, TEXAS

LIFTING JACK

Application filed February 1, 1930. Serial No. 425,283.

This invention relates to a lifting jack designed primarily for use in connection with motor vehicles, but it is to be understood that it may be employed in any connection for which it is found applicable, and the invention has for its object to provide, in a manner as hereinafter set forth, a lifting jack for raising the vehicle, one wheel at a time when bogged down, out of a hole or depression in a road surface or to enable the positioning of tread chains on the wheels, as well as for lifting the body of the vehicle to enable the replacing of springs, or for any other purpose.

Further objects of the invention are to provide, in a manner as hereinafter set forth, a lifting jack which is simple in construction and arrangement, strong, durable, compact, thoroughly efficient in its use, of a size capable of being stored in the vehicle when not in use, conveniently operated, readily assembled and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be had which will fall within the scope of the claims hereunto appended.

In the drawings wherein like reference characters denote corresponding parts throughout the several views:—

Figure 1 is a side elevation of a lifting jack in accordance with this invention.

Figure 2 is an elevation looking toward the front thereof.

Figure 3 is a front elevation, partly in section.

Figure 4 is a side elevation partly in section and illustrating the device in operative position with respect to the axle of a motor vehicle and with the axle lifted by the device.

A lifting jack, in accordance with this invention, includes a base 1, preferably of rectangular contour and which is provided

at its center with a socket 2, opening at the upper face of the base. Positioned within the socket 2 is a standard or pedestal 3 of the desired height and formed with a socket 4 opening at the top edge of the standard. 55 Arranged within the socket 4, projecting upwardly therefrom the desired distance is a coupling bar 5 which extends between and is fixed to a pair of oppositely disposed upwardly extending supports referred to generally at 6, 7.

As the supports 6, 7 are of the same construction, but one will be described as the description of one will apply to the other. Each support includes a circular casing 8 65 opening at its inner side and a triangular shaped carrier 9 for the casing 8. Each support is formed with an integral, inwardly extending, right angularly disposed flange which is coextensive with the sides and top 70 of the support. The part of the flange, indicated at 10 is semi-circular. The remaining parts of the flange, which are indicated at 11, 12 depend from the ends of part 10 at inward inclinations toward each other. The 75 inner face of each support is formed with a semi-circular flange 13, which is oppositely disposed with respect to flange part 10 and merges into the ends of the latter and into the upper ends of flange parts 11, 12. 80

The flange part 10 and flange part 13 provide the annular body of the casing 8. The part 14 of the support forms the outer side wall of the casing 8. The lower end portions of the flange parts 11, 12 of one support 85 are welded, as at 15 to the lower end portions of the flange parts 11, 12 of the other support and are also welded to the coupling bar 5. The lower ends of the supports are spaced a substantial distance above the upper end of standard 3.

Formed integral with and disposed centrally of the flange part 10, at the top of the latter, is an upstanding, apertured lug 16 which is of a width corresponding to that of 95 flange part 10. The purpose of lug 16 will be presently referred to.

Formed integral with the outer face of flange part 10 and disposed substantially at right angles with respect to the lug 16, is 100

a right angularly disposed, outwardly projecting, apertured lug 17, and, adjacent lug 17, flange part 10 is cut away to provide an opening 18 for a purpose to be presently referred to.

5 The part 14 of each support, which provides the outer side wall of casing 8 is formed at its center with an opening 19 for a purpose to be presently referred to.

10 When the supports 6, 7 are set up, the lower ends thereof are connected together and the upper ends spaced from each other, but said upper ends are coupled together by a tie bolt 20 extending through the apertured lugs 16 and having its head 21 abutting against the outer face of one lug 16 and its other end projecting from the other lug 16 and carrying a securing nut 22 which abuts against the outer face of the last mentioned lug.

15 When the supports 6, 7 are secured together, the lugs 17 are arranged in opposed, parallel, spaced alignment and journaled in said lugs 17 is a shaft 23, provided at each end with a crank handle 24. The shaft 23 projects laterally from the outer faces of the supports 6, 7 a substantial distance. Fixed to the shaft 23 and arranged in spaced relation is a pair of pinions 25 which extend 20 through the openings 19 and into the casing 8 and mesh with a pair of gear wheels 26. Each gear 26 is arranged in a casing 8. The gears 26 are carried by a shaft 27 extended through the openings 19 formed in the 25 portions 14 of the supports. The shaft 27 is driven from the gears 26, on the rotation of the pinions 25. The shaft 27 has each end mounted in a journal 28 formed on the outer face of each of the supports 6, 7.

30 Fixed to the shaft 27, centrally thereof and spaced from the gears 26 is a sprocket pinion 29 having positioned against each side thereof, a retaining disk 30. The disks 30 are bodily carried with the sprocket pinion 29 and are of materially greater diameter than said sprocket pinion 29 for the purpose of retaining a lifting chain 31 on the pinion 29. The lifting or elevating chain 31 is of the link type and carries at one end a coupling 35 device in the form of an annulus 32, provided with lateral hooks 33. The annulus 32 is adapted to be positioned upon a hub for the purpose of lifting or elevating the latter when the stretch 34 of the chain 31 is elevated on the rotation of the pinion 29. As illustrated, the annulus 32 is mounted upon the hub 35 of a wheel 36. The hooks 33 are for the purpose of engaging the rim or spoke of the wheel for elevating the same. The coupling device provides means for connecting the chain 31 to the object to be lifted.

60 The coupling bar 5 carries a hook 37 adapted to have the stretch 38 of the chain 31 connected thereto to prevent the lowering of

stretch 34 when the object has been raised to the desired height.

It is thought the many advantages of a lifting jack, in accordance with this invention can be readily understood, and although the preferred embodiment of the invention is as illustrated and described, it is to be understood that changes in the details of construction can be had which fall within the scope of the invention as claimed.

75 What I claim is:

1. A device for the purpose set forth comprising a pair of oppositely disposed flanged supports, said supports being connected together at their lower ends and spaced from each other from their connected lower ends, means for connecting the upper ends of said supports together, each support providing a casing having depending therefrom a carrier for the casing, a shaft journaled in and extending through said casings and having fixed thereto a pair of spaced gears, each gear being arranged in a casing, a sprocket pinion fixed to said shaft between said gears, a lifting chain travelling over and operated by said pinion and having its stretches projecting from the front and rear of said supports, a supporting standard, means for connecting said supports to the standard, and means mounted on said casings for rotating said gears.

2. A device for the purpose set forth comprising a pair of oppositely disposed flanged supports, said supports being connected together at their lower ends and spaced from each other from their connected lower ends, means for connecting the upper ends of said supports together, each support providing a casing having depending therefrom a carrier for the casing, a shaft journaled in and extending through said casings and having fixed thereto a pair of spaced gears, each gear being arranged in a casing, a sprocket pinion fixed to said shaft between said gears, a lifting chain travelling over and operated by said pinion and having its stretches projecting from the front and rear of said supports, a supporting standard, means for connecting said supports to the standard, means mounted on said casings for rotating said gears, and chain retaining means fixed to each side of said sprocket pinion.

3. A device for the purpose set forth comprising a pair of oppositely disposed flanged supports, said supports being connected together at their lower ends and spaced from each other from their connected lower ends, means for connecting the upper ends of said supports together, each support providing a casing having depending therefrom a carrier for the casing, a shaft journaled in and extending through said casings and having fixed thereto a pair of spaced gears, each gear being arranged in a casing, a sprocket pinion fixed to said shaft between said gears, a lift-

ing chain travelling over and operated by said pinion and having its stretches projecting from the front and rear of said supports, a supporting standard, means for connecting said supports to the standard, means mounted on said casings for rotating said gears, a hook carried by the means for connecting said supports to the standard and adapted to engage in one of the stretches of said chain, and a coupling device connected to the free end of the other stretch of the chain.

In testimony whereof, I affix my signature hereto.
